UNITED STATES PATENT OFFICE.

WILLIAM CECIL BOWER, OF BIRMINGHAM, ALABAMA.

DESIGN FOR A BADGE.

SPECIFICATION forming part of Design No. 24,532, dated August 13, 1895.

Application filed June 22, 1895. Serial No. 553,736. Term of patent 3½ years.

To all whom it may concern:

Be it known that I, WILLIAM CECIL BOWER, a citizen of the United States, residing at Birmingham, in the county of Jefferson and State 5 of Alabama, have invented a certain new and useful Design for Campaign-Badges; and I do declare the following to be a full, clear, and exact description of the invention, such as will enable others skilled in the art to which 10 it appertains to make and use the same.

This invention relates to a certain new and useful design for campaign-badges; and to this end the characteristic features of my design consist in the representation of a fish of 15 the species known as the "tarpon" or "silver

king" and directly beneath the fish and suspended therefrom by two chains a winged insect or bug.

Having thus described my design, what I claim to be new, and desire to secure by Letters Patent, is—

The design for a campaign-badge, substantially as herein shown and described.

In testimony whereof I affix my signature in presence of two witnesses.

WILLIAM CECIL BOWER.

Witnesses:

J. P. LONNESTER,
T. M. SANFORD.
